UNITED STATES PATENT OFFICE.

ALEXANDER LINDGREN, OF MANCHESTER, NEW HAMPSHIRE, ASSIGNOR OF ONE-HALF
TO HOVEY E. SLAYTON, OF MANCHESTER, NEW HAMPSHIRE.

BOOT OR SHOE.

Application filed April 7, 1923. Serial No. 630,487.

To all whom it may concern:

Be it known that I, ALEXANDER LINDGREN, a citizen of the United States, and resident of Manchester, in the county of Hillsborough 5 and State of New Hampshire, have invented an Improvement in Boots or Shoes, of which the following description, in connection with the accompanying drawings, is a specification, like letters on the drawings 10 representing like parts.

My present invention relates to an improvement in the art of manufacturing boots and shoes, and to a novel and economical method of construction, whereby simple, 15 efficient and readily adjustable means are provided for varying the foot contacting part of the shank or arch.

In the manufacture of orthopedic footwear, it is of great importance to provide 20 means to enable the shank portion, viz, the insole or insole member along the arch, to be moved into desired position for the wearer. This is particularly advantageous in corrective footwear wherein the arch sustaining portion of the shoe is manufactured 25 in quantities and yet should be separately fitted for each wearer, and each shoe should be adjusted for the foot of the wearer. Many prior efforts have been made to provide 30 footwear with orthopedic appliances, particularly along the shank or arch portion, but these prior methods and apparatus have been unsatisfactory, difficult and expensive to install, extremely inaccessible to 35 make desired fittings or adjustments, and have proven to be too difficult and cumbersome for general use. Such prior devices where the shank adjusting members could only be reached from the inside of the shoe, 40 for example, necessitated the constant removal of the shoe from the foot of the wearer, in fitting same, manipulation of the shank or arch adjusting portions by guess work and then again fitting the shoe to the 45 wearer and testing and trying same.

My present invention obviates all this difficulty and enables orthopedic footwear to be manufactured by standard shoe making machines, substantially along present established methods, simply constructed and economically manufactured, and yet with a simple, efficient and readily accessible adjusting means, which can raise, lower or otherwise fit the arch supporting part of 50 the shoe to any desired position when fitting

the shoe to the wearer and without the wearer removing the shoe. Thus my invention permits a pair of shoes of appropriate size to be fitted to a wearer, and without removal, without guess work, and while the 60 wearer is applying a constant pressure therein or standing, the shank or arch adjusting devices can be manipulated in each foot to a perfect supporting position. Furthermore, my present invention enables 65 these adjusting devices to be constantly varied and raised or lowered, thus affording a progressive course of corrective treatment for the wearer, without changing footwear, and by simple means capable of operation 70 by the wearer himself.

In carrying out my invention I may apply the same to any of the present standard shoes made. In the manufacture of a welt or McKay shoe embodying my invention, I 75 prefer to split the rear portion of the insole from the heel forwardly, so that the shoe may be assembled on a last, lasted, and the upper and soles permanently united, leaving the upper or foot contacting portion of the 80 insole free. It will be appreciated that I may utilize a plurality of layers for this insole portion, instead of splitting the insole to provide these layers as above noted. In any event, I provide a free insole portion 85 from the heel forwardly to approximately the forepart or ball of the shoe, which layer I propose to adjust with regard to height, relatively with the shoe, and with the shank or arch portion of the wearer. Thus I may 90 even apply to a turn shoe a separate insole member secured at the forepart and with the adjusting means of my present invention applied thereto.

Preferably I utilize a metallic member, 95 secured, riveted or held at the forward part adjacent the ball of the shoe, and provide means operable longitudinally and concealed in the heel, to move this metallic member to raise or lower the position of the 100 free shank portion of the insole.

Such means consists preferably in a threaded member concealed in a suitable recess in the heel, and operable either from the heel breast or from the rear of the heel, 105 and rotatable to position and adjust the flexible member and to automatically lock the same in adjusted position.

Further details of the invention, important advantages and novel combinations 110

will be hereinafter more fully pointed out and claimed.

Referring to the drawings, illustrating a preferred embodiment of my present invention as applied to a typical McKay shoe,

Fig. 1 is a side view, partly in cross-section, of my novel shoe utilizing my process and illustrating the invention;

Fig. 2 is a bottom plan view with the heel in cross-section on the line 2—2 of Fig. 1;

Fig. 3 is a longitudinal cross-sectional view substantially a duplicate of Fig. 1, excepting that the accessible adjusting means is open to the rear of the heel;

Fig. 4 is a cross-sectional view on the line 4—4 of Fig. 1; and

Fig. 5 is a perspective of the metallic shank member.

In the drawings I have illustrated a typical McKay shoe having an outsole 1, upper materials 2, heel 3 and insole 4. This insole is preferably split from the heel portion forwardly, forming a bottom layer 5 and an upper layer 6. As above noted the insole may, if desired, consist in a plurality of layers, the important feature being to so construct the shoe that the uppermost or foot contacting layer 6 is free to be moved vertically from the insole member 5 to which latter the upper and outsole are attached by stitching 7 or equivalent upper and sole attaching means. In making my improved shoe by my present process, as thus far described, I assemble the insole and upper materials in the usual manner, last the same, apply the outsole, secure the lasted upper and outsole together, in this case by the through and through stitching, without special or unusual processes. I can fit the upper layer 6 in an appropriate recess in the last during the lasting process, can fit temporarily a clinching plate between the two members 6 and 5, if desired in McKay lasting, or keep the two layers separate by any suitable means. As thus far made, my shoe follows present standard methods. Thereupon I cut a slight recess 10 in the outsole 1 adjacent the heel portion. This is intended to permit the downwardly extending lug portion 12 of my adjustable metallic member 15 to be extended. The shank member is fitted between the layers 6 and 5, and rigidly secured at the forward end, approximately at 14 by a suitable rivet or the like.

This rivet 14 may extend through both layers of the insole, if desired, or also through the outsole if desired, or as shown, it is fitted through the bottom layer 5 of the insole, thus concealing the same. The longitudinal notch or recess 16 is also cut in the lower insole member 5 to permit the insertion of the shank member 15, similar to and adjacent the recess 10 in the outsole. These recesses 10 and 16 are preferably of suitable

width for the size of the metallic member 15.

I can form this member 15 of any desired width, it being an important feature of my present invention that the adjustable metallic member 15 can extend entirely across the width of the shoe if desired, can be of any suitable contour, shape or other supporting feature, the layer 6 naturally following the shape and contour of the metallic supporting member 15. Furthermore such supporting members can be easily attached to and removed from a shoe after it has been completed, if desired, although I prefer to carry out my present process of fitting the shank member 15 to the insole before the heel is attached, and thus building the same in the shoe. The large capability of adjustment afforded by my invention obviates the necessity of changing the shank members after the shoe is once constructed.

Longitudinal movement of this shank member 15 acts to vary the height of the insole portion 6 at the shank and to raise and lower same as desired to fit the contour of the arch of the foot of the wearer, and of each shoe. In order to provide for this adjustment or movement longitudinally, I secure to the outsole 1 a lug 20 adapted to receive the shank portion of a rotatable threaded shaft 21, the lug 20 holding the same between the head 22 and a collar 23 secured to said shank. The shank 21 is approximately threaded to fit the correspondingly threaded recess in the depending lug 12 of the shank member 15. This rotation of the shank 21 affords means to raise or lower the middle part of the shank 15 and consequently of the insole 6 between the rivet 14 and the lug 12, the recesses 10 and 16 permitting the sliding action of the member 15 to produce this result. I prefer to provide the head 22 of the shaft with a slot to receive a screwdriver, and the lug 20 may be held to the outsole 1 by a pair of rivets 123 as shown in Fig. 4.

The form illustrated in Fig. 1 shows the slotted end of the shaft 21 positioned forwardly or adjacent the heel breast of the heel 3, and therefore I provide the heel 3 to be attached to this form with a corresponding recess 25 to cover, protect and conceal the lugs 20, 12 and shaft 21, as well as to afford room for the lug 12 to effect this sliding action during manipulation of the shaft 21. In the form shown in Fig. 3, the slotted end of the shaft is open rearwardly or at the back of the heel, and therefore I provide this heel 30 with a longitudinal recess 31 appropriately positioned therefor. In the latter instance the recess is so slight as to be scarcely noticeable and further if desired the head 22 can be covered by wax or the like and the entire heel burnished, finished, etc., thus keeping out dirt, water and the like, as well as concealing the adjusting means, while permitting its ready

accessibility. In the form shown in Fig. 1 the slotted head is directly concealed at the juncture of the shank of the outsole and heel breast, and the entire shoe has the complete appearance of standard types of footwear, capable of manufacture in any desired style, size or leather. My present invention thus enables an attractive, economical and efficient orthopedic shoe to be provided, capable of continual and progressive adjustments for curative action on the arch of the foot of the wearer, and furthermore, has the inside appearance of any high grade type of shoe, without openings, recesses or other objectionable features, while the adjusting devices operate efficiently and are concealed, as well as protected by the heel. Furthermore the shank supporting metallic member enables the insole and consequently the arch of the foot to be positively supported for as great an extent, widthwise and lengthwise, as may be desired, and this metallic shank member may be of any suitable metal, spring steel, composition, brass or of non-corrosive material if desired, so that it will not deteriorate, rust or lose its efficiency and usefulness. The adjustments can be instantly and readily effected by means of an ordinary screwdriver and with the shoe constantly on the wearer, thus securing an actual fitting of the shank supporting portion to the foot while both foot and shoe are under tension—a broadly new feature. As I am advised that this feature is a distinct novelty in this art I am claiming the same broadly herein. Also my process of making an improved shoe and the novel adjusting apparatus, are claimed herein broadly, as well, also, as the prepared insole fitted with my adjusting apparatus. It will be appreciated that I may apply the member 15 at various times during the process of making my improved shoe, preferably fitting the same as above explained. I can, however, carry out my invention by first preparing an insole for a shoe, either welt or McKay construction, forming the loose layer part either by splitting or by applying an extra layer, fitting the shank member thereto by the rivet 14, forming for this purpose the recess 16. With the prepared insole as thus described it is then assembled on the last, the shoe lasted, the outsole fitted with the recess 10 and the shoe completed. I may, if desired, also form a portion of the groove 31 in the adjacent part of the sole, if desired, particularly in the form shown in Fig. 3. My invention is further described and defined in the form of claims as follows:

1. A boot or shoe of the kind described, having a foot contacting insole portion free for vertical movement relatively with the rest of the shoe, a metallic member fitted

under said freely moving portion, means securing said metallic member adjacent the forepart of the shoe, and means operating from the outside of said shoe to effect the movement of said metallic member and vary the vertical position of the free insole portion. 70

2. A boot or shoe of the kind described, having a foot contacting insole portion free for vertical movement relatively with the rest of the shoe, said freely movable portion being independent of openings, recesses or the like on its foot contacting surface, a metallic member fitted under said freely moving portion, means securing said metallic member adjacent the forepart of the shoe, and means operating from the outside of said shoe to effect the movement of said metallic member and vary the vertical position of the free insole portion, said operating means acting to simultaneously adjust and lock the metallic member in adjusted position. 85

3. A boot or shoe of the kind described, having a smooth surfaced insole layer for contact with the foot of the wearer, said layer being free of attachment to the shoe along the shank and heel portions, a metallic arch supporting member under said layer, means to permanently attach said arch supporting member adjacent the forepart of the shank, a recess in the outsole, a lug secured to said arch supporting member extending through said recess, a rotatable threaded member engaging the lug, and means holding said member whereby rotation of the threaded member effects the longitudinal movement of the said lug and arch support, and means from the outside of the shoe permitting access to the rotatable member to rotate the same. 100

4. A boot or shoe of the kind described having an insole split into two separate portions, an upper and a lower, from a point adjacent the rear of the sole to the extreme heel portion, the lower portion, together with the sole portion, being secured in the usual manner to the upper and outsole, a metallic member fitted between said upper and lower portions, means securing said metallic member adjacent the joining part of the upper and lower portions with the forepart, and means operable from the outside of said shoe to effect a movement of the metallic member in a vertical direction about its fastening point whereby the unsecured upper portion of the insole is movable therewith and operating means acting to simultaneously adjust and lock the metallic member in adjusted position. 115

In testimony whereof, I have signed my name to this specification.

ALEXANDER LINDGREN.
